(57) **CLAIM**

The ornamental design for a label, as shown and described.

DESCRIPTION

The patent or application file contains at least one drawing executed in color. Copies of this patent or application with color drawing(s) will be provided by the Office upon request and payment of the necessary fee.

FIG. 1 is a front view of a first embodiment of a label; FIG. 2 is a front view of a second embodiment of a label; FIG. 3 is a front view of a third embodiment of a label; FIG. 4 is a front view of a fourth embodiment of a label; FIG. 5 is a front view of a fifth embodiment of a label; FIG. 6 is a front view of a sixth embodiment of a label; FIG. 7 is a front view of a seventh embodiment of a label; and, FIG. 8 is a front view of an eighth embodiment of a label.

The greyscale shading in the Figures represents a contrast in appearance.
